Application August 12, 1943, Serial No. 498,338

3 Claims. (Cl. 102—70.2)

1

Our invention relates to the detonation of explosive projectiles with controlled time delay and is directed to the use of what may be termed a condenser circuit for delayed action in fuses. Such a condenser circuit is charged at some initial potential distribution and is designed for progressive change in that distribution in such manner as to apply an effective potential to suitable igniting means after a predetermined time interval.

One of the important problems in designing a time fuse incorporating a condenser circuit is to provide a thoroughly reliable and foolproof safeguard against accidental or premature detonation. It is especially difficult to avoid serious hazard in the act of initially charging the fuse with the necessary potential.

Various safety expedients are known to the art. It has been suggested, for example, that a generator be built into the fuse for operation after the projectile is released, thereby to delay charging of the condenser circuit. Other suggestions have involved mechanical expedients for use during the charging operation or special mechanical relationships between the fuse and the cooperating charging device.

One object of our invention is to meet this safety problem with complete success by simple structural means confined to the projectile and the associated holding means for the projectile. An important advantage of such an arrangement is that a simple and rudimentary charging device, free of complicated safety features, may be employed.

Many of the prior art suggestions may be used for projectiles of relatively large size which afford ample room for elaborate circuit arrangements and for moving parts, but such suggestions cannot in practice be used for projectiles of relatively small caliber, 20 mm. shells, for example. A further object of our invention is to provide a safe and highly efficient fuse construction especially suitable for small caliber projectiles, a construction involving no moving parts whatsoever and lending itself to compact design. In this regard, a feature of our invention is the use of certain safety shunts designed to be opened automatically upon release of the projectile. Various practices of our inventions are based on various novel concepts of how such automatic action may be insured by simple expedients.

In a certain practice of our invention, we have the two-fold object, first, of employing a relatively low charging potential to achieve a relatively high ultimate potential and, second, of avoiding hazard in the charging operation by

2

employing an igniter that is non-responsive to the initial relatively low potential applied by the charging device.

In designing condenser circuits for the present purpose, it is not difficult to arrange for accurate delay periods within a narrow range of time periods, especially within a range of relatively short time periods. It is difficult, however, to achieve sufficient accuracy over wide ranges and especially for relatively long time delays. One object of certain practices of our invention is to achieve accuracy over wide ranges of time values by novel arrangements involving the use of two or more variable charging potentials. In one of these practices, it is our purpose to employ one or more auxiliary or modifying condensers for the desired flexibility in time delay. In another teaching, we propose to achieve the desired accuracy and range by a novel form of charging device in which the relative values of two charging potentials are varied automatically for different time adjustments in a succession of time ranges.

More specific objects and advantages of our invention will be apparent in the following description taken with the accompanying drawings.

In the drawings, which are to be considered as illustrative only:

Fig. 1 is a wiring diagram of one arrangement under our concept that may be employed for the delayed detonation of explosive projectiles;

Fig. 2 shows the same diagram modified for elimination of moving parts and for adaptability to small caliber projectiles;

Fig. 3 is a diagrammatic view in cross section of an explosive shell incorporating the electrical arrangement of Fig. 2;

Fig. 4 is a wiring diagram of one of our arrangements involving the use of two safety shunts;

Fig. 5 is a diagrammatic view in cross section of an explosive shell incorporating the arrangement indicated in Fig. 4;

Fig. 6 is a wiring diagram of one of our electrical arrangements involving the use of two different charging potentials with a safety shunt;

Fig. 7 is a modification of the diagram of Fig. 6;

Fig. 8 is a diagrammatic view in cross section showing an explosive shell incorporating the electrical arrangement shown in Fig. 7;

Fig. 8a is a view similar to Fig. 8 showing a second structural arrangement for incorporating the principles illustrated by Fig. 7;

Fig. 9 is a wiring diagram of another differentially charged circuit incorporating a safety shunt;

Fig. 10 is a diagrammatic view in cross section

of an explosive shell incorporating the electrical arrangements shown in Fig. 9;

Fig. 10a is a view similar to Fig. 10 of another structural arrangement based on Fig. 9.

Fig. 11 is a wiring diagram indicating how one or more modifying condensers may be added to the basic circuit;

Fig. 12 is the wiring diagram of Fig. 11 modified to permit independent charging of the additional condenser;

Fig. 13 is a wiring diagram illustrating our concept of initially charging a fuse from a low potential source and subsequently automatically increasing the potential after the projectile is released;

Figs. 14, 15, 16 and 17 are graphs explaining certain relationships involved in certain practices of our invention;

Fig. 18 is a diagram indicating the construction of an adjustable charging device based on relationships shown in Figs. 16 and 17.

Fig. 19 is a graph indicating relationships involved in a second form of adjustable charging device; and

Fig. 20 is a diagram indicating the construction of this second form of adjustable charging device.

It is to be understood that our invention is widely applicable to projectiles, the invention having utility not only for explosive shells discharged from guns, but also for such explosive projectiles as aerial bombs, mines of various types, torpedoes and grenades. The term "projectile" as used hereinafter covers any of such explosive devices or the like.

In many practices of our invention a holding means for a projectile has a special cooperative relationship with the timing circuits employed for delayed detonation. The term "holding means" may refer to various devices in various practices of our invention and is therefore to be broadly construed. For example, if the projectile is shot from a gun, either the shell case or the gun, or both, may be regarded as the holding means. If the projectile is an aerial bomb, the holding means may be a bomb rack or any part of aircraft from which the bomb is released. It will be apparent that the invention is applicable even to hand grenades since the thrower's hand or some device retained in the thrower's hand may be the holding means under our concept.

In the simple form of our invention illustrated by Fig. 1, tank condenser or ignition condenser 20 is in series with what may be termed a timing condenser 21, the two condensers being mutually opposed and being connected to a common ground 22. Interconnecting the potential or charge-receiving terminals of the two condensers are an igniter 23 and a current-blocking means 25 arranged in series. The timing condenser 21 is shunted by a suitable resistance 26 serving as a current-leakage means and may also be shunted by a wire 27 controlled by an impact switch 28. For the purpose of charging the condenser circuit, a charging contact 30 is connected to the potential side of the condenser 20 by a wire 31 and is connected to the potential side of the condenser 21 by a wire 32, there being a normally closed safety switch 33 controlling current flow through the wire 32. The safety switch 33 is designed to open automatically whenever the projectile is released. In a shell, for example, we may use an inertia switch that snaps open in response to acceleration of the shell in the gun barrel. This actuation of a safety protective device, which, prior to such actuation, will normally prevent any current from

flowing through the igniter, is referred to as "arming" of the projectile.

In preparation for release of the projectile, a suitable charging means is applied to the described circuit. In the practice of the invention exemplified by Fig. 1, it is contemplated that the charging means will be in continuous communication with the condenser circuit up to the moment the projectile is released. In Fig. 1 the charging means is shown as including a charging contact 35 connected to a grounded battery 37. If the delayed action fuse is not grounded through the holding means for the projectile, the charging means may also include a grounding contact for the fuse circuit.

As soon as communication between the charging device and the condenser circuit is broken by release of the projectile, current leakage through the resistance 26 causes the charge on the timing condenser 21 to decrease with a corresponding drop in potential across the timing condenser, the charge on the tank condenser 20 meanwhile remaining constant in the absence of any closed conducting path. As the voltage across the timing condenser decreases, an increasing potential drop is established across the current-blocking means 25. When this potential difference across the current-blocking means reaches a predetermined value, a conducting path is established to permit flow of current from the tank condenser 20 to a lower potential level, such current flow causing the igniter 23 to be energized for detonation of the projectile.

The igniter 23 may be a conventional heating cap or detonating primer, or may be a suitable filament such as employed in flash bulbs. The current-blocking means 25 may be a gap means such as a gaseous tube in which the gas becomes ionized to form a conducting path whenever the potential across the tube rises to a predetermined value. In some practices of the invention, the current-blocking means may be simply a gap in the circuit closed by a suitable dielectric which breaks down at a given potential across the gap. It is apparent that the current-blocking means 25 and the igniter 23 are closely related in function and may therefore be jointly covered by the term "igniter" or the term "igniting means"; in fact, the function of blocking current and the function of ignition proper may conceivably be combined in one element by using an explosive dielectric to bridge a gap in the circuit.

Fig. 2 is identical in most respects to Fig. 1, as indicated by the use of corresponding numerals to designate corresponding parts. In this second circuit, however, there is no switch along the wire 33 since it is contemplated that some provision will be made for automatically breaking the wire 33 when the projectile is released. The wire 33 may be broken at any point, for example, at the dotted line y—y, or both the wire 33 and the wire 31 may be broken as indicated by the dotted line x—x. The arrangement is especially suitable for projectiles of relatively small caliber as illustrated by Fig. 3.

Fig. 3 shows a projectile or shell 40 mounted in a case 41, the projectile containing suitable explosive material and a fuse body 42. The nose 40 of the projectile may be provided with an impact plunger 43 to close the previously mentioned impact switch 28. The charging contact 30 for the fuse circuit may be of any suitable construction and may be placed at any suitable location. Fig. 3, by way of example, shows

the charging contact 30 in the form of a concentric metal ring in the base of the case 41, the ring being suitably insulated from the metal material of the base. The previously mentioned wires 31 and 33 extend from the fuse body 42 through suitable apertures in the base of the shell 40 and are terminally connected to the annular charging contact 30, preferably at spaced points thereof as indicated.

To arm the shell shown in Fig. 3 for delayed detonation, a suitable charging means incorporated in the associated gun construction is automatically brought into communication with the annular charging contact 30, as indicated diagrammatically in Fig. 3. As soon as the projectile 43 is released following detonation of the primer 44 in the base of the case 41, the movement of the projectile away from the case causes the two wires 31 and 33 to be broken thereby destroying the safety shunt and making the condenser circuit operative for delayed ignition of the projectile charge.

In the circuit shown in Fig. 4 a tank condenser 45 is connected to a charging contact 46 by a wire 47 and a timing condenser 48 shunted by a bleeder resistance 50 is connected to the same charging contact by a wire 51. Current through the wire 51 is controlled by a normally closed safety switch 52. The potential sides of the two condensers 45 and 48 are also interconnected in series by a gaseous tube 53 or equivalent current-blocking means. The other sides of the two condensers 45 and 48 are connected to ground by wires 55 and 56 respectively, current through the wire 56 being controlled by a normally closed safety switch 57. The ground sides of the two condensers are interconnected in series by an igniter 58. For instantaneous firing, a wire 60 may connect the potential side of the condenser 45 with the ground side of the condenser 48, current flow through the wire being controlled by a normally open switch 61 designed to close when the projectile strikes an object.

If the circuit shown in Fig. 4 is employed in a projectile of large caliber, the two safety switches 52 and 57 may be inertia switches of a well known type designed to open when the projectile is initially accelerated. Prior to the opening of the two switches, no operative potential difference can be established across the gaseous tube 53 and no effective current can flow through the igniter 58. Prior to release of the projectile, a complementary charging means in communication with the charging contact 46 maintains both of the condensers at the same potential with small current flow continuously through resistance 50 to ground. When the projectile is released thereby breaking communication with the complementary charging means and causing the two switches 52 and 57 to open, the circuit operates in the previously described manner to build up a potential across the gaseous tube 53 and ultimately cause detonation through the igniter 58.

In view of previous discussion, it will be readily apparent that the circuit shown in Fig. 4 may be adapted for small caliber projectiles by omitting the two switches and providing for breaking the shunt wires. Instead of arranging for wires to be broken to open the safety shunts, we may design the projectile for mechanical opening of the shunts incidental to release of the projectile from the holding means.

In Fig. 5, in which we illustrate this latter concept, we show a small caliber shell 62 mounted

in a casing 63, there being a fuse body 65 inside the shell. At the end of the shell is shown an impact plunger 66 for actuating the previously mentioned impact switch 61. Fig. 5 also shows how we may arrange the wires 47, 51, 55 and 56 of the wiring diagram in Fig. 4. Wires 55, and 56 terminate in two contacts 67 and 68 respectively, these contacts being insulated from the material of the shell 62 but being positioned to touch the metal of the case 63 thereby to provide ground connections. Wires 47 and 51 terminate respectively in two contacts 70 and 71 in a socket 72 formed in the bottom of the shell 62. Mounted in the case 63 is a rigid conductor 73 designed to enter the socket 72 and provide a conducting path from the two contacts 70 and 71 to the previously mentioned charging contact 46. In this particular construction, the charging contact 46 is in the form of a metal ring mounted in the base of the case 63 with suitable insulation. Fig. 5 shows how the previously described charging means, including the contact 35 and the battery 37 may touch the charging contact 46 when the projectile is placed in a gun.

There are certain inherent limitations in circuits in which a single charging contact is employed for charging both the tank condenser and the timing condenser in the manner described above. Since the charging voltages applied to the two condensers are necessarily equal, time adjustment can be achieved only by varying the common charging voltage. This fact may be readily understood by referring to Fig. 14 in which the curve represents voltage decay across the timing condenser and v_t represents the striking voltage of the gaseous tube or other current-blocking means incorporated in the circuit. One limitation is that zero time delay can be obtained only by using an infinite initial charging voltage. Another limitation is that the charging voltage must be lowered to increase the time interval so that a relatively long delay period will require that the circuit be operated at a relatively low energy level.

These limitations can be eliminated by charging the two condensers differentially. For convenience, an arrangement wherein the condensers are charged equally may be referred to as a simplex circuit and an arrangement providing for differential charging may be referred to as a duplex circuit.

The advantages of a duplex circuit may be understood by referring to Fig. 15, in which E_2 represents an unvarying voltage applied to the tank condenser in our circuit and the curve of voltage decay represents a range of potentials through which the timing condenser may be initially charged. It is apparent that zero time delay may be obtained simply by charging the time condenser initially with a voltage less than E_2 by the amount v_t . For a relatively short delay period the initial charge on the timing condenser would be less than E_2 by an amount slightly less than v_t . For relatively long delay periods the initial charge on the timing condenser would be higher than the voltage E_2 . It is clear that a duplex circuit provides a greater range of time adjustment than a simplex circuit without the necessity of dropping to an undesirably low energy level.

Fig. 6 shows a duplex circuit in which a charging contact 75 is connected to the potential side of a tank condenser 76 by a wire 77 and a second charging contact 78 is connected to the po-

tential side of a timing condenser 80 by a wire 81, the timing condenser being shunted by a bleeder resistance 82. A wire 83 interconnects a gaseous tube 84 and an igniter 85, the tube and igniter interconnecting the potential sides of the two condensers in series. Both of the condensers are grounded as shown. For percussion detonation, an impact switch 86 may control a wire 87 that extends from the above mentioned wire 83 to ground. Our safety shunt for this circuit is shown as a wire 88 from wire 83 to the charging contact 75, current through this shunt wire being controlled by a normally closed safety switch 90.

The manner in which the circuit shown in Fig. 6 functions may be readily understood from our previous discussion. For relatively short time delays, the voltage E_1 applied to the charging contact 78 is relatively low, this voltage being increased for longer delay periods. If the circuit is employed in a large caliber projectile, the safety switch 90 may be operated by inertia as heretofore suggested.

As heretofore stated, the "igniter" may be considered as the igniter 85 proper or the igniter 85 in combination with the gaseous tube 84. Accordingly, our safety shunt may straddle the igniter 85 alone as shown in Fig. 6 or may by-pass both the igniter 85 and the gaseous tube 84 as shown in Fig. 7.

Fig. 7 is largely similar to Fig. 6 as indicated by the use of corresponding numerals for corresponding parts. It will be noted that the safety shunt wire 89 in Fig. 7 is connected with the terminal of the gaseous tube 84 on the side towards the timing condenser 80 and that a resistance 94 is introduced between the gaseous tube and the timing condenser.

The advantage of the arrangement in Fig. 7 over the arrangement in Fig. 6 is that the potential E_2 is applied to both sides of the gaseous tube and therefore cannot cause the tube to strike in the course of the charging procedure. The resistance 94 is introduced because the difference in potential between E_1 and E_2 necessarily exists between the gaseous tube and the timing condenser.

Either the circuit of Fig. 6 or the circuit of Fig. 7 may be incorporated in a small caliber projectile, the shunt switches being omitted and means being provided to break the shunt wires. Fig. 8, for example, shows how the circuit of Fig. 6 may be used in a small caliber shell.

Fig. 8 shows the usual shell 91 mounted in a case 92. Inside the shell 91 is a fuse body 93 and the above mentioned impact switch 86 positioned for actuation by an impact plunger 95. The charging contacts 75 and 78 of Fig. 7 may be mounted anywhere on the holding means or case 92. By way of example, Fig. 8 shows the two contacts 75 and 78 in the form of suitably insulated metal rings exposed on the periphery of the case 92. A wire 96 is shown connected to the metal shell of the projectile 91 for the purpose of grounding the two condensers 76 and 80. Also shown in Fig. 8 are wires 77, 81 and 88 of the diagram in Fig. 7, wire 81 being connected to the ring-shaped contact 78 and wires 77 and 88 being connected to the other ring-shaped contact 75.

When the projectile shown in Fig. 8 is placed in a gun, a suitable charging means is automatically brought into electrical communication with the two ring-shaped contacts 75 and 78 as indicated diagrammatically in Fig. 8. When the

projectile is released by detonation of explosive material in the case 92, the three wires 77, 81 and 88 are automatically broken. The manner in which the circuit functions thereafter for delayed detonation is apparent.

While Fig. 8 shows the two charging contacts 75 and 78 mounted on the case 92, these charging contacts may be mounted on the projectile 91. Fig. 8a indicates how the arrangement in Fig. 8 may be modified to shift the contacts from the case to the shell. Note that the case 91 in this figure is of conventional construction there being no necessity for modifying the case in any manner.

The projectile 98 in Fig. 8a is provided with two insulated exterior rings to serve as contacts 75 and 78 respectively. The ground wire 96 from the fuse body 93 is connected as before to the material of the projectile. Wire 81 is connected to the upper ring 78 and wires 77 and 88 are connected to the lower ring 75.

A feature of the arrangement shown in Fig. 8a is the concept of making the wire 88 relatively long so that the wire may be passed through suitable apertures in the bottom of the projectile to form a loop 100 in the interior of the case 97. The purpose of providing such a loop is to make the safety shunt wire 88 vulnerable to the explosion that propels the projectile. It is contemplated that the explosion will destroy at least a portion of the wire forming the loop 100 thereby opening the safety shunt. While no further provision for breaking the shunt is necessary, some means may be provided on the case 97 to engage the loop and insure mechanical severance of the wire as the projectile leaves the case. For example, a pin or hook 101 may be mounted on the interior of the case 97 to extend through the loop 100.

Fig. 9, illustrating another arrangement of our duplex circuit, shows a charging contact 102 connected by a wire 103 to the potential side of a tank condenser 105 and shows a charging contact 106 connected to the potential side of a timing condenser 107 by a wire 108, the timing condenser being shunted by the usual bleeder resistance 110. The potential sides of the two condensers are connected in series with a gaseous tube 111 and the ground sides of the two condensers are interconnected in series by an igniter 112. In this particular circuit our safety shunt is on the ground side of the condensers. By way of example, we show a wire 113 for grounding the tank condenser 105 and a second wire 115 grounding the timing condenser 107. A safety switch 116 is shown for breaking current through the wire 115 but obviously such a switch may be employed to control current through wire 113 instead. For instantaneous detonation, we show a shunt across the condenser 107 controlled by an impact switch 117.

If the circuit of Fig. 9 is employed in a large caliber projectile, the safety switch may be operated by inertia or in any other automatic manner. On the other hand, if it is desirable to omit the safety switch, provision may be made to break either or both of the two wires 113 and 115.

The provision for breaking the wire or wires of the safety shunt on the ground side in Fig. 9 may be in accord with any of the teachings exemplified by Figs. 3, 5, 8 and 8a. Thus, in Fig. 10 we show an arrangement in which both wires 113 and 115 are isolated mechanically when the projectile is released.

Fig. 10 shows a projectile 118 mounted in a

case 119 in the usual manner. The projectile contains the usual fuse body 120, above which is shown an impact plunger 121 for closing the previously mentioned impact switch 117. The two grounding wires 113 and 115 terminate respectively in two insulated contacts 122 and 123 positioned on the periphery of the projectile 118 to touch the metal surface of the case 119. As heretofore suggested, the charging contacts 102 and 106 of the circuit in Fig. 9 may be placed anywhere on the case 119. In the present construction, the two charging contacts 102 and 106 comprise two insulated concentric metal rings in the base of the case 119, one ring being connected to wire 103 and the other ring being connected to wire 108.

The manner in which the arrangement in Fig. 10 functions may be readily understood. When the projectile 118 leaves the case 119, the two wires 103 and 108 are automatically broken, and the ground connections shunting the igniter are opened by movement of the contacts 122 and 123 away from the case.

The purpose of Fig. 10a is to indicate how the arrangement in Fig. 10 may be modified to place both of the charging contacts on the projectile. The two charging contacts 102 and 106 are in the form of insulated rings, wire 103 being connected to the ring 102 and the wire 108 being connected to the ring 106. Since the two rings 102 and 106 are insulated from each other, it is not necessary to break the wires 103 and 108. Both of the wires 113 and 115 are connected to the metal material of the projectile for grounding but at least one of the two wires is arranged for automatic severance. Thus Fig. 10a shows the wire 115 connected terminally to the projectile but passed through suitable aperture through the projectile to form a loop 125 in the interior of the case. As heretofore suggested, a pin or hook 126 may extend from the case through the loop 125 but it is not necessary.

The purpose of Fig. 11 is to exemplify our concept of incorporating in a duplex circuit one or more modifying condensers to affect the rate at which potential drops across the timing condenser thereby to vary the period of time delay. Those skilled in the art will readily understand that the addition of such modifying means affords additional flexibility in the operation of the circuit.

In Fig. 11, a charging contact 127 is connected by a wire 128 to the potential side of the tank condenser 130 and a second charging contact 131 is connected by a wire 132 to the potential side of a timing condenser 133, the timing condenser being shunted by the usual bleeder resistance 135. A suitable gaseous tube 136 is shown in series with the potential sides of the two condensers while an igniter 137 is shown in series with the ground sides of the condensers. Wires 140 and 141 ground the tank and timing condensers respectively. The circuit as described to this point will be recognized as corresponding to Fig. 9.

We show only one auxiliary or modifying condenser 142 in Fig. 11 but it will be understood that any number of such additional condensers may be employed. A wire 143 connects the potential side of the timing condenser 133 with the potential side of the modifying condenser 142 and a suitable bleeder resistance 145 connects the ground side of the modifying condenser with the ground side of the timing condenser. The ground side of the modifying condenser 142 is connected to ground through a wire 146.

It is apparent that the modifying condenser 142 will be initially charged with the same potential E_1 as the timing condenser 133 and that the modifying condenser, like the timing condenser, will have its charge opposed to the charge on the tank condenser 130. If this circuit is incorporated in a projectile, some means is provided for cutting off the three condensers from each other, for example, by severance of the three wires 140, 141, and 146 along the line $x-x$ by any of the various expedients heretofore suggested.

When the projectile having the circuit in Fig. 11 is released, thereby isolating the charging contacts 127 and 131 from each other and thereby 15 breaking the three ground wires, current flows through the resistance 135 to lower the potential difference across the timing condenser 133. The rate at which this potential difference decreases, however, is modified by current flow through the 20 bleeder resistance 145 from the modifying condenser 142. Ultimately the voltage opposing the charge on the tank condenser 130 decreases until detonation occurs.

Fig. 12 shows a variation of Fig. 11 corresponding parts being indicated by corresponding numerals. Fig. 12 differs from Fig. 11 in providing for independently charging a modifying condenser 147 so that three different potentials may be employed for adjustably varying the period 25 of time delay. In addition to the charging contacts 127 and 131 previously mentioned, the circuit includes a third charging contact 148 that is connected by a wire 150 to the potential side of the modifying condenser 147. The potential sides 30 of the timing condenser 133 and the modifying condenser 147 are interconnected by a bleeder resistance 151 and the ground sides of the two condensers are interconnected by a wire 152. The manner in which the circuit functions may 35 be understood without further explanation.

Fig. 13 illustrates our concept of how a relatively low charging potential may be employed in the field to provide a relatively high igniting potential after a projectile is released, the increase in potential being accomplished by shifting a plurality of condensers from parallel relation to series relation. Fig. 13 shows a plurality of ignition or tank condensers, there being, for example, three such condensers 153, 154 and 155. The potential side of the tank condenser 153 is connected by a wire 157 to a charging contact 158 and is connected by a wire 160 to one side of an igniter 161. The tank condenser 154 is connected on its potential side to a charging contact 162 and a switch contact 163. In like manner, the tank condenser 155 is connected on its potential side to a charging contact 165 and a switch contact 166.

The ground side of tank condenser 153 is connected to a switch member 167 that normally rests against a grounded contact 168 but is adapted to swing automatically against the switch contact 163 when the projectile is released from its holding means. In like manner, the ground side of the condenser 154 is connected to a switch member 170 that initially rests against a grounded contact 171 but subsequently swings automatically against switch contact 166. The third tank condenser 155 is permanently 60 grounded. It is apparent that the arrangement provides for initial parallel charging circuits through the three tank condensers 153, 154 and 155.

To complete the final ignition circuit, the 75 second side of the igniter 161 is connected by a

wire 173 to a suitable gaseous tube 175 and the gaseous tube is connected in turn by a wire 176 to the potential side of a timing condenser 177. The timing condenser 177, which is shunted by the usual timing resistance 180, is connected on its potential side to a charging contact 181 and is connected to ground on the other side by a wire 182. A safety switch 183 may be employed connected so as to shunt the igniter 161.

Fig. 13 shows diagrammatically a charging means in which four contacts corresponding to the four charging contacts 158, 162, 165 and 181 of the circuit are all energized at the same potential by a common battery 172, the battery affording a relatively low potential. In some practices of our invention, however, the various condensers may be charged at different potentials.

When the projectile is released from its holding means, the four charging contacts become isolated from each other and the two switches 167 and 170 are operated by inertia or other automatic action to shift the plurality of tank condensers from parallel relation to series relation thereby adding the charges to produce a relatively high potential across the circuit opposed by the charge on the timing condenser 177. As has previously been described, the release of the projectile will operate to open the normally closed safety switch 183, or to sever the igniter shunt wires along the line $x-x$, thereby serving to "arm" the projectile. The opposing potential across the timing condenser progressively decreases because of current flow through the resistance 180 and eventually the high potential across the tank condenser becomes effective to jump across the gaseous tube 175 and detonate the igniter 161.

For accuracy in time measurement by our duplex circuit the slope of a curve of voltage values plotted with respect to time should be such that given voltage differences represent commensurate differences in time periods. If the curve is too steep, a given change in potential represents an undesirably small change in time; on the other hand, the same change in potential along a flattened curve represents an excessively large change in time.

We have found that for accurate time control different relationships between E_1 , the timing condenser charge, and E_2 , the tank condenser charge, must be employed in different time ranges. Thus, for accuracy in an initial range of relatively short time periods, E_2 must be relatively high, whereas over a range of relatively long time periods E_2 must be relatively low. We have further discovered that these two extreme ranges of time changes may be correlated in such manner as to afford a smooth and gradual progression of time values. One manner of correlating the two extreme ranges of time changes is by introducing a mid range.

The graph in Fig. 16 shows an initial range of relatively small time periods in which E_2 is relatively high. It is assumed, by way of illustration, that in a particular duplex circuit the striking voltage v_t of the gaseous tube is 400 volts and that E_2 throughout the initial range is maintained at 900 volts, E_2 minus v_t equalling 500 volts. In the midrange of time values E_2 substantially equals E_1 , both diminishing progressively as indicated. Since E_2 is constant over the initial range and since E_2 substantially equals E_1 at the end of the initial range, variation in time over the initial range is produced by variation in the value of E_1 , E_1 being relatively low for

instantaneous ignition and rising to substantially equal E_2 at the end of this initial time range.

In the final range of relatively long time periods, E_2 is again held substantially constant at a relatively low value (E_2 minus v_t equals 100 v.) and variations in time are again produced by variations in the value in E_1 . At the start of this final range, E_1 substantially equals E_2 but with increasing time values over the range, E_1 progressively rises above E_2 .

Fig. 17 shows graphically the relation between the charging voltages E_1 and E_2 over the three ranges of time adjustment.

In Fig. 18 we indicate diagrammatically how a rheostat arrangement may be employed in a charging device to apply potentials E_1 and E_2 selectively for any desired value over the three ranges of time. A control member 185 shown in dotted lines carries a first brush or wiper 186 that is connected to a charging contact E_1 by a wire 187 and also carries a second brush or wiper 188 that is connected by a wire 190 to a charging contact E_2 . Movement of the control member 185 with reference to a time scale 191 causes the wiper 186 to traverse a rheostat resistance generally designated 192 and simultaneously causes the wiper 188 to traverse a second rheostat resistance generally designated 193.

The rheostat resistance 192 for controlling potential E_1 is divided into three ranges by connection with a low voltage wire 203 and a high voltage wire 194, the ranges corresponding to the previously mentioned initial, mid and final time ranges. The initial time range is defined by a low voltage connection 195 and a high voltage connection 196; the midrange is defined by the high voltage connection 196 and a second low voltage connection 197; and the final time range is defined by the low voltage connection 197 and the second high voltage connection 198. Thus, the potential E_1 rises progressively as the control member 185 moves to the right until a maximum value is reached at connection 196 whereupon potential E_1 drops progressively until contact 197 is reached and finally the potential rises to the maximum again at connection 198.

The rheostat resistance 193 comprises a contact 200 extending over the initial time range, a resistance 201 extending over the midrange, and a second contact 202 extending over the final time range. The contact 200, the resistance 201, and the contact 202 are in series, the contact 200 being connected to the high voltage wire 194 and the contact 202 being connected to the low voltage wire 203. By virtue of this arrangement, the potential E_2 varies in the desired manner as the control member 185 is moved around the time scale 191, the potential E_2 being constant at a relatively high voltage in the initial time range, progressively decreasing in the midrange and again remaining constant in the final range. It will be noted that the described arrangement causes E_1 to equal E_2 in the midrange, both values increasing or decreasing synchronously with movement of the control member 185.

The manner in which such a charging device is employed may be readily understood. The operator merely adjusts the operating member 185 for whatever period of time delay in detonation is desired, the operator being guided by reference to the time scale 191.

Instead of employing a midrange between the two extreme ranges of time as described above, we may in some practices of our invention omit the midrange and provide for direct correlation

by arranging for the values E_2 and E_1 at the end of the initial range to equal the values of E_2 and E_1 at the beginning of the final range. The relationship may be understood by referring to Fig. 19. Note that E_1 progressively rises towards the relatively high value of E_2 over the initial range and that in the final time range E_1 is substantially constant while E_2 progressively decreases in value.

In Fig. 20 we indicate diagrammatically how a rheostat arrangement may be incorporated in a charging device to supply potentials E_1 and E_2 over two time ranges correlated in the manner suggested by Fig. 19.

A control member 205 shown in dotted lines carries a first brush or wiper 206 that is connected to a charging contact E_1 by a wire 207. The control member also carries a second brush or wiper 208 that is connected by a wire 210 to a charging contact E_2 . For cooperation with the contact 206 we show a rheostat means comprising a resistance 211 and an elongated contact 212 in series, the outer end of the resistance 211 being connected to a low voltage lead 213 and the elongated contact being connected to a high voltage lead 215. For cooperation with the contact 208 we show a second rheostat means comprising an elongated contact 216 and a resistance 217 in series, the elongated contact 216 being connected to the high voltage lead 215 and the outer end of the resistance 217 being connected to the low voltage lead 213. It may be readily understood that movement of the control member 205 to adjust charges E_1 and E_2 for various time intervals will cause the voltages E_1 and E_2 to vary in value in accord with Fig. 19.

The specific embodiments of our invention set forth above for the purpose of disclosure will suggest to those skilled in the art various changes and substitutes under our basic concepts; we reserve the right to all such departures that lie within the scope of our appended claims.

We claim:

1. In an electric ignition device for delayed detonation of an explosive projectile after the projectile is released from a holding means, the combination of: condenser means in the projectile to hold an electric charge, an igniter in the projectile; charging means for electrical communication with said condenser means while said projectile remains on said holding means; means to apply the charge of the condenser means to said igniter with time delay after the projectile is released from said holding means; a normally closed safety shunt across said igniter to prevent flow of electric current therethrough; an electric conductor included in said shunt, said conductor being attached to said projectile; and means on the holding means engaging said conductor to sever the conductor and thereby open the shunt when said projectile moves away from said holding means.

2. In a delayed ignition device for a unit, which unit comprises an explosive projectile, holding

means therefor, and a propelling charge, the combination of: a condenser circuit in the projectile; charging means for contact with said unit to establish a given potential distribution in said circuit prior to explosion of said propelling charge; means to progressively change the potential distribution in said condenser circuit over a period of time after the projectile is propelled from said holding means; an igniter responsive to the potential in said system at a predetermined point in said progressive change in distribution; and a shunt including a wire across said igniter to prevent energization thereof, at least a portion of said wire being positioned outside of said projectile and in the area occupied by said propelling charge whereby the explosion of said propelling charge will destroy at least a portion of said wire and open said shunt.

3. In an electric ignition device for delayed detonation of an explosive projectile after the projectile is released from a holding means, the combination of: condenser means in the projectile to hold an electric charge, an igniter in the projectile; charging means for electrical communication with said condenser means while said projectile remains on said holding means; means to apply the charge of the condenser means to said igniter with time delay after the projectile is released from said holding means; a normally closed safety shunt across said igniter to prevent flow of electric current therethrough; an electric conductor included in said shunt, said conductor being attached to said projectile and extending into the holding means; and means associated with the holding means and including an explosive charge in the holding means for severing said conductor whenever the projectile is fired from the holding means by exploding said explosive charge.
